Primary Examiner — Leah Macchiarolo*Assistant Examiner* — Alexandria Dubus(74) Attorney, Agent, or Firm — Schroeder Law PC(57) CLAIM

The ornamental design for a deck box, as shown and described.

DESCRIPTION

FIG. 1 is a top perspective view of a deck box showing our new design;

FIG. 2 is a front elevation view thereof;

FIG. 3 is a rear elevation view thereof;

FIG. 4 is a top view thereof;

FIG. 5 is a bottom view thereof;

FIG. 6 is a left side elevation view thereof; and,

FIG. 7 is a right side elevation view thereof.

The broken lines shown represent unclaimed subject matter and form no part of the claimed design.
